UNITED STATES PATENT OFFICE

CHARLES ANTHONY HILL, OF NEW YORK, N. Y.

TOY SAVINGS-BANK.

1,169,033.

Specification of Letters Patent. Patented Jan. 18, 1916.

Application filed November 7, 1914. Serial No. 870,833.

To all whom it may concern:

Be it known that I, CHARLES A. HILL, a citizen of the United States, and a resident of the city of New York, borough of Manhattan, in the county and State of New York, have invented a new and Improved Toy Savings-Bank, of which the following is a full, clear, and exact description.

The object of the invention is to provide a new and improved toy savings bank arranged to permit of conveniently introducing coins of different denominations, to prevent surreptitious abstraction of the accumulated coins, and to allow of conveniently opening the bank at the time the same is filled with coins.

In order to accomplish the desired result, use is made of a container formed of telescoping outer and inner sections provided with registering coin slots for the introduction of the coins, a guideway extending across the inner container section and having a slot in register with the said registering container slots, and a spring-pressed plunger slidably in said guideway and normally closing a portion of the said registering container slots.

A practical embodiment of the invention is represented in the accompanying drawings forming a part of this specification, in which similar characters of reference indicate corresponding parts in all the views.

Figure 1 is a side elevation of the toy savings bank; Fig. 2 is a cross section of the same; Fig. 3 is a sectional side elevation of the same on the line 3—3 of Fig. 2; and Fig. 4 is an inverted sectional plan view of the same, on the line 4—4 of Fig. 2.

The container for the coins is made of two telescoping outer and inner sections A and B of cup shape, and with the open end of one section adjacent the closed end of the other section when the two sections are assembled, as plainly shown in the drawings.

The container formed in the manner described is provided in its sides with one or more coin slots C disposed vertically at one end of the container. The upper end of the inner container section B is provided with a diametrically extending tubular guideway D provided in its bottom with a slot E in transverse alinement with the corresponding container slot C and in each end of the guideway D is mounted to slide a plunger F normally seated against the inner face of the container section B to

close the upper portion of the corresponding container slot C. A spring G extends within the guideway D and presses at its ends against the plungers F so as to hold the same normally in outermost position with a view to close the upper portion of the container slot C, as previously mentioned and shown to the left in Fig. 2 and in Fig. 4. The lower portion of each container slot C is less in height than the diameter of the smallest coin (a dime) that can be introduced, it being understood that the entire height of the slot exceeds the diameter of the largest coin (say a quarter) that can be introduced, but I do not limit myself to the particular length of slot as the same is governed by the sizes of the coins of different denominations to be introduced.

When it is desired to introduce a coin, the operator inserts it edgewise in the container slot C so that the edge of the coin engages the plunger F and on pressing the coin inwardly the plunger is caused to slide inwardly against the tension of the spring G, and on a further inward movement of the coin the latter eventually drops into the inner section B. When this takes place the plunger F is returned to its normal outermost position by the action of the spring G.

In order to keep the container sections A and B normally in locked position, use is made of struck-up registering lugs and indentations H, H' in the sides of the container, the lugs H being preferably on the outer section A and engaging the corresponding indentation H' formed in the inner container section B, as plainly shown in Fig. 2. It will be noticed that when the container sections A and B are assembled, the registering lugs and indentations H and H' engage one another, so as to hold the container sections locked in assembled position. When the container is filled with coins and the user tries to insert another coin then the pressure exerted by this coin against the coins in the container tend to force the lugs and indentations H, H' apart so that the inner container section B aided by the weight of the coins, readily slides out of the outer container when the latter is held in the hand so that the sections A and B come apart to allow of emptying the section B of its accumulated coins. When this has been done the sections A and B are again telescoped to allow reuse of the savings bank.

In practice the sections A and B are preferably made of sheet metal corrugated in the direction of the length of the sections to render the savings bank exceedingly strong and durable.

Having thus described my invention, I claim as new and desire to secure by Letters Patent:

1. A savings bank, comprising a container made in telescoping outer and inner sections of cup shape, the open end of one section being adjacent the closed end of the other section, the sides of the said sections being provided with registering coin slots adjacent one end of the container, the slots extending in the direction of the height of the container, a tubular guideway secured to the inner faces of the inner section at the open end thereof and extending diametrically across the said section, the said guideway having a slot in its bottom in transverse alinement with the said registering slots, and a spring-pressed plunger slidable in the said guideway and normally closing the upper portion of the said registering coin slots.

2. A savings bank, comprising a container made in telescoping outer and inner sections of cup shape, the open end of one section being adjacent the closed end of the other section, the sides of the said sections

being provided with registering coin slots adjacent one end of the container, the coin slots extending in the direction of the height of the container, the sides of the said sections being provided with struck-up registering lugs and indentations to lock the sections together, a tubular guideway extending diametrically across the open end of the inner section, the said guideway having a slot in transverse alinement with the said registering slots, and a spring-pressed plunger slidable in the said guideway and normally closing the upper portion of the said registering coin slots.

3. A savings bank, comprising two telescoping cup-shaped sections having vertical registering coin slots in opposite sides adjacent one end, a tubular guideway in the upper portion of the sections and extending from side to side of the sections, said guideway having in its bottom a slot registering with the coin slots, plungers in the guideway, and a spring in the guideway between the plungers.

In testimony whereof I have signed my name to this specification in the presence of two subscribing witnesses.

CHARLES ANTHONY HILL.
